UNITED STATES PATENT OFFICE.

WASEL LUOFF, OF MOND MINE, ONTARIO, CANADA.

PISTOL-SWORD.

1,278,363.

Specification of Letters Patent. Patented Sept. 10, 1918.

Application filed March 8, 1918. Serial No. 221,152.

To all whom it may concern:

Be it known that I, WASEL LUOFF, a subject of the Emperor of Austria, residing at Mond Mine, in the Province of Ontario 5 and Dominion of Canada, have invented certain new and useful Improvements in Pistol-Swords, of which the following is a specification.

The primary object of the invention is 10 the provision of a combined sword and pistol adaptable for instant use as a fire arm as well as a sword when the device is operatively assembled, the blade of the sword being rendered removable when the occasion 15 requires.

A further object of the device is the provision of a pistol sword in which the blade of the sword is operatively associated with the barrel of the pistol for permitting the 20 ready use of the pistol during the loading and firing operations, the structure possessing great strength and serving a double purpose as a weapon for the soldier in charge of the device.

25 In the drawing forming a part of this application and in which like reference characters refer to corresponding parts throughout the several views,

Figure 1 is a side elevation of the device 30 partially broken away,

Fig. 2 is a top plan view thereof,

Fig. 3 is a longitudinal sectional view taken upon lines III—III of Fig. 1.

Fig. 4 is a transverse sectional view taken 35 upon line IV—IV of Fig. 1.

Fig. 5 is a perspective view of the rear end portion of the sword blade and

Fig. 6 is a perspective view of the forward portion of the pistol member with 40 parts removed.

It being understood that the invention is in the nature of a combined weapon for the use of soldiers, the same broadly consists of a pistol or revolver 10 having a stock or 45 hilt 11 and a forwardly projecting barrel 12, the said barrel being provided with a blade 13 serviceable as a sword.

The main casting 14 of the revolver 10 has the barrel 12 pivoted thereto as at 50 15 in the usual manner while a cartridge cylinder 16 is secured to the hinged plate portion 17 of the barrel in the usual manner as by a screw 18 secured within an opening 19 of the said plate 17. A guard 20 for the 55 hand of the operator connects the casting 14 with the stock 11 while a tubular extension

21 of the said casting accommodates the usual firing mechanism, not shown, and adapted to be tripped by the trigger 22 positioned adjacent the stock 11 and having a 60 finger guard 23. A hooked lug 24 outwardly projects from the blade 13 adjacent its rear end 25 adapted for reception within an inwardly opening slot 26 in the plate 17 when the cylinder 16 and screw 18 are removed. 65

The barrel 12 fits within a side groove 27 of the blade 13 and beneath a top ledge 28 of the blade. With the blade 13 mounted upon the pistol 10 in this manner and with the cylinder 16 and screw 18 in their proper 70 positions, the said cylinder will be accommodated for turning within a recess 29 in the blade end 25. A cross-head or spring latch 30 is provided at the rear end of the 75 ledge 28 adapted for locking reception between upstanding ears 31 upon the casting 14 in substantially the usual manner when the device is closed.

It will be seen that when the device is 80 assembled and arranged as shown in Fig. 1 of the drawing, the stock 11 may be grasped for operating the trigger 22 in firing the pistol 10 while the latch 30 may be released at will for pivotally shifting the barrel 12 upon its hinge 15 for arranging the cylinder 85 16 in its open arrangement for the purpose of reloading the same. The barrel is then swung with the cylinder to its closed position and the latch 30 in locking engagement with the ears 31. 90

Sufficient clearance is provided by the arrangement of the groove 27 and the position of the blade 13 upon the barrel to provide clearance for the bullets when fired from the pistol 10. When it is desired to 95 use the device as a sword, the tubular casing or hilt 21 may be grasped by the hand for wielding the blade 13 and at which times the member 20 serves as a guard for the hand of the soldier. A serviceable combination 100 weapon is provided especially adaptable for cavalry use, and combining lightness in weight with serviceability in a single implement of warfare. 105

What we claim as new is:—
1. A pistol sword comprising in combination with a pistol casting having a barrel member hinged thereon and formed with an inwardly opening slot, a blade provided with a side groove and a top ledge adapted to accommodate the said barrel member, an attaching lug projecting from said blade 110

arranged within said slot when the device is assembled and a retaining latch at the inner end of said ledge adapted for locking engagement with the pistol casting when the barrel member is arranged in its closed position.

2. In combination with a pistol having a casting and a hilt and stock member positioned in angular arrangement at one end 10 of the casting, a barrel for the pistol having a slotted plate hinged upon the forward end of the casting, a cartridge cylinder removably carried by the plate in closing arrange-

ment with the slot thereof, a blade having a side groove and a top ledge adapted for 15 mounting upon the said barrel and having a recess adapted for accommodating the cartridge cylinder, a projecting hooked lug upon the blade arranged through the slot of said plate and a spring-pressed latch carried by the rear end of the ledge adapted for engaging the casting of the pistol when the device is in its closed operative arrangement.

In testimony whereof I affix my signature. 25
WASEL LUOFF.
